F. W. MORSE

SPRING STRUCTURE FOR BEDS, COUCHES, OR THE LIKE

Filed April 6, 1923

Patented Mar. 3, 1925.

1,528,125

UNITED STATES PATENT OFFICE.

FRANK W. MORSE, OF SAN FERNANDO, CALIFORNIA.

SPRING STRUCTURE FOR BEDS, COUCHES, OR THE LIKE.

Application filed April 6, 1923. Serial No. 630,308.

To all whom it may concern:

Be it known that I, FRANK W. MORSE, a citizen of the United States, residing at San Fernando, in the county of Los Angeles and 5 State of California, have invented certain new and useful Improvements in Spring Structures for Beds, Couches, or the like, of which the following is a specification.

The primary object of my present invention is to provide a new and improved construction of springs, more especially adapted for use in couches, beds and bed lounges and in the practical application of which the desired elasticity of the spring is obtained at any and all portions of the bed alike; a spring that will render to a person of heavy weight, on one side of the bed, and a person of light weight, at the other side of the bed, the same relative elasticity, with 15 no sag in the center, and in which the form of construction of the spring greatly multiplies the effectiveness and durability of such springs.

Another object of my invention is to provide an improved construction of spring, of the single strand type, that is especially well adapted for being applied across the frame of the bed, couch, lounge, etc. and for being combined with the intermediate flexible supporting members placed at proper intervals, according to the width of the frame of the bed or couch.

Again, my invention provides an improved construction of single strand spring 35 device of the kind mentioned, that can be readily made in various sizes to constitute the particular shapes and sizes of couches, ordinary beds or folding beds of the davenport style, or for seats and back rests, and 40 which, when applied for use, will give ease and comfort alike to a heavy person, resting in the depression made by such persons, and to an infant resting in the depression of its own weight, and each resting in its own 45 position.

A further object of my invention is to provide a spring device of the general character stated that may be easily and securely applied to a frame and lashed in permanent and substantial position by any and all means of lashings known and used in the application and lashing of spiral bed springs.

A still further object of this invention is 55 to provide an improved construction of single wire strand spring for couches, beds and

the like having such shape that, when operatively applied, an edge spring is obtained in a true line and which provides ease and comfort should one desire to set 60 on the edge of the bed or couch; a spring construction in which the alignment is across the bed, also across the body resting on the bed and which assures perfect elasticity to the said resting body.

With the above general objects in view and other minor objects that will hereinafter be apparent, my invention embodies, in a spring of the general type stated, certain features of construction and peculiar arrangement of parts that will be fully explained in the following detailed description, specifically mentioned in the appended claims and illustrated in the accompanying drawings, in which:

Figure 1 is a diagrammatic plan view of a preferred form of bed frame with a sufficient number of my improved springs to illustrate a practical application of my present invention.

Figure 2 is a cross section of the bed taken substantially on the line 2—2 of Figure 1.

Figure 3 is a detail perspective view of one of the improved constructions of springs shown in Figures 1 and 2.

Figure 4 is a perspective view of a slightly modified form of spring device that is adapted to be used on couches and which will hereinafter be specifically referred to.

Figure 5 is a detail perspective view 90 illustrating the manner in which the spring strands are lashed apart to prevent squeaking.

In the drawings, to illustrate the practical application of my improved construction of spring device, I have shown a substantially complete bed frame, but it is to be understood that the said frame may be of any suitable construction for properly supporting the spring elements and it is to be understood that no claim is made in this application to the framing, per se, since my present invention is wholly directed to the spring formation.

The spring elements are especially designed for being operatively applied to and lashed together on the bed framing in any desired manner, a number of different modes of lashings being indicated in Figure 1 and hereinafter referred to.

In the drawings I have shown my present construction of springs as especially de-

signed for use in connection with a couch or bed and while but three transversely disposed spring devices are shown at one end and one spring at the other end of the 5 frame it is to be understood that any desired number of springs of proper size and flexibility of wire are assembled such as will ensure a comfortable and durable bed.

While a full size bed spring structure is 10 outlined in Figure 1 of the drawings, it will also be understood that one-quarter, two-thirds or couch sized bed springs may be equipped with the same type of spring device by reducing the number of supporting 15 members of the spring in the construction thereof, see Figure 4.

The bed frame, as shown, includes six parallel spring carriers or rails designated 1, 2, 3, 4, 5 and 6 and they are held in rigid 20 relation by a number of transverse braces 7 and at the head and foot ends the several rails 1-6 are each fitted with or terminate in uprights 8 that constitute means at the head and foot ends of the frame for anchoring 25 the ends of the flexible lashing means which extend the full length of the bed and are securely connected at their ends to the upright 8 in any approved manner.

The lashing means for holding the springs 30 against rattling and in the desired upright position may be of any of the well known lashings commonly used in the art of making spring beds. In Figure 1 of the drawings is illustrated a number of different types of 35 lashings, which may be in the nature of a continuous coil spring 9, one of which is positioned over each of the rails 1, 3, 4, 6; a single wire strand 10 whose opposite ends join with close coil springs 11 that are shown 40 as anchored to the uprights 8 at the ends of the rail 2; a combination of continuous coil spring and wire core 12 as is shown located over the rail 4; or a twisted wire strand 13 that is shown as located over the rail 5. In 45 practice in all types of lashings, each strand of the cross spring device is lashed apart with a firm grip for the purpose of eliminating squeaking, see Figure 5.

Referring now to Figure 3 which illustrates one of the completed bed spring elements diagrammatically shown in Figures 1 and 2, it will be seen that the said spring element is bent to shape from a single wire strand, and when made of a size to suit a 55 full width bed, it includes a number of top or parallel crown portions, and parallel bottom portions and a series of uprights or supports of V-shaped form, the various crown portions, bottom portions and the 60 V-shaped supports being connected by coiled portions as shown.

In the form shown in Figure 3 the wire strand, at the beginning, of the construction thereof, is bent into a coil 14 formed at the 65 bottom of an outer V-shaped upright or

supporting member 15 the apex of which is bent into a coil 16. At the upper end the supporting member 15 terminates in a coil 17. From the coil 17 the strand extends 70 across forming a straight or crown portion 18.

At the termination of the relatively long crown portion 18 the wire strand is coiled at 75 19 and formed to provide an intermediate V-shaped support 20 including a coil 21. The intermediate V support 20-21 joins by the coil 22, the bottom portion 23 which extends across and joins, by the coil 24, with an inner V-shaped support 25 which includes a coil 26. The inner V-shaped support 25 joins, by the coil 27, the central, relatively short, crown portion 28. From the center of the central crown portion 28 the wire strand is bent, successively, into a coil 29, a V-shaped inner support 30 including the 80 coil 31, a coil 32, a bottom portion 33, a coil 34, an intermediate V-shaped support 35 including a coil 36, a coil 37, a relatively long crown portion 38, a coil 39, an outer V-shaped support 40 including a coil 41 at the apex thereof and terminates in a coil 42, 85 to form a half portion which is an exact duplicate of the portions 14-28 inclusive and hereinbefore described in detail.

At the commencement of the coil 14 and 90 at the termination of the coil 42 the wire strand is extended as at 43 to form a means for connecting the said ends to the bed frame as hereinafter explained.

All of the spring devices used in a bed 95 structure, such as is indicated in Figure 1, are constructed alike and all of such devices, which extend entirely across the bed have one outer vertical support anchored to the outside bed rail and the other outer vertical support anchored to the opposite outside bed rail and all of the upper or crown portions of the spring devices are joined with the lashing members and all of the transversely disposed bottom portions are 100 suitably anchored in the rails 2, 3, 4 and 5 as shown, or upon the equivalent portions of any desired type of frame structure.

While the construction of the spring 105 described and shown is a preferable embodiment of my invention, that is,—with bends, coils and supporting members at a uniform distance along a single strand of wire and the supporting members at a uniform height, it is to be understood that the several supporting members or coils and the bends formed in the wire may be varied in 110 height and distance to meet the requirements of the bed and couch so that ease, strength and durability may be assured.

In Figure 4 of the drawings is illustrated 115 a slightly modified form of my improved construction of spring device, which form, while more particularly adapted for use in couches, folding beds and davenports, may 120

also be used for the smaller three-quarter and two-third sizes of beds and in the said modified form the same general arrangement of the spring is present as in the larger sizes of springs used for the full size bed.

In the modified form the single strand is shown as bent to produce two centrally disposed V supporting members 44 joined by a straight across bottom portion 45 and two 10 parallelly disposed and oppositely extended crown portions 46 which terminate in outer V-shaped supporting members like those of the preferred form and whose lower coiled ends terminate in hook portions 47 15 adapted for being fixed in any suitable manner on the outside rails of the couch, bed or davenport.

The point of connection of the various inner V supports (of the preferred form or 20 spring construction) with the bottom or bearing portions may also be formed as loops as shown in the modified form instead of coils as shown in the preferred form.

From the foregoing description, taken in 25 connection with the accompanying drawings, the novel details of construction, the advantages and the manner of application of the spring structure to the various uses to which it is applicable, will be readily apparent to those skilled in the art to which the invention relates.

What I claim is:

1. A spring composed of a single strand of wire formed to comprise opposite ends 35 formed to provide fastening elements, V-shaped supports whose upper ends merge with cross over portions that constitute parallel overlapped crown portions, other V-shaped supports merging with the inner 40 overlapped ends of said crown portions and whose lower ends merge with a cross over portion constituting a bottom bearing for said spring.

2. A spring composed of a single strand of

wire formed to comprise opposite ends formed 45 to provide fastening elements, V-shaped supports whose upper ends merge with cross over portions that constitute overlapped parallel crown portions, V-shaped supports merging with the inner overlapped ends of said 50 crown portions and whose lower ends merge with inwardly extending cross over bottom portions overlapping in parallel relation and constituting a bottom bearing for said spring, a centrally disposed crown portion and additional V-shaped supports merging with the inner ends of said cross over bottom portions and the outer ends of said central crown portion for supporting the latter upon the former.

3. The combination with a bed frame of a plurality of equi-distantly spaced parallelly positioned spring elements each formed from a single strand of wire to comprise opposite ends providing means of connection to the frame, V-shaped supports whose upper ends are coil wound and merge with cross over portions that constitute overlapped parallel crown portions, other V-shaped supports whose upper ends are coil wound and merge with the inner overlapped ends of said crown portions and whose lower ends merge with inwardly extending cross over bottom portions overlapping in parallel relation and constituting a bottom bearing 55 for the spring elements, a centrally disposed crown portion and additional V-shaped supports whose lower ends merge with the inner ends of said cross over bottom portions and whose upper ends are coil wound and merge with the outer ends of said central crown portions for supporting the latter on the former; and lashing devices connected to and through each aligning set of coils at the V-shaped supports tops 60 and to the frame to flexibly secure the spring units in spaced relation.

FRANK W. MORSE.
